UNITED STATES PATENT OFFICE.

CHARLES WALDREN STANTON, OF MOBILE, ALABAMA.

APPARATUS FOR STEAMING WOOD.

SPECIFICATION forming part of Letters Patent No. 735,608, dated August 4, 1903.

Application filed October 10, 1902. Serial No. 126,776. (No model.)

To all whom it may concern:

Be it known that I, CHARLES WALDREN STANTON, a citizen of the United States, residing at Mobile, in the county of Mobile and State of Alabama, have invented new and useful Improvements in Apparatus for Steaming Wood, of which the following is a specification.

My present invention relates to an apparatus for steaming wood and other material, and is especially adapted for steaming wood to boil the sap and moisture therefrom prior to treating the same to any suitable waterproofing or preserving composition.

It is the prime purpose of the invention to provide an apparatus the parts of which are so constructed and arranged as to save both the liquid and the gaseous products resulting from the steaming operation. To these ends the invention comprises the novel features of construction and arrangement of parts in an apparatus of the above-specified type.

In the annexed drawing the figure represents a longitudinal sectional view of my improved steaming apparatus.

Referring to the drawing the reference-numeral 1 designates a hermetically-sealed tank or vessel of any suitable shape in cross-section, said tank being provided at its opposite ends with doors 2, through which the wood or other material to be treated may be introduced into the vessel. Leading into the vessel, preferably at the top thereof, is a steam-inlet pipe 3, provided with a valve 4.

The reference - numeral 5 designates an outlet - pipe through which the steam and other products may pass. The end of said pipe 5 terminates into a condensing-worm 7^b, arranged in a suitable receptacle 7^c, in which is placed a suitable cooling medium. The end of the worm 7^b projects through the receptacle 7^c and terminates in a pipe 7^d for the discharge of the products of condensation into a suitable tank 6, having a liquid seal therein, such as water. The seal in the receptacle 6 prevents any back pressure of air or otherwise to the worm and, further, pre-

vents the escape to the atmosphere of any of the uncondensed products.

The reference-numeral 7 denotes a draw-off pipe for the products of condensation. The tank 6 is also provided with a filling-cock 8. The tank 6 is also provided with a draw-off pipe 9 for the uncondensed gases. These uncondensed products may be discharged into the atmosphere or carried to any suitable point and used for any suitable purpose. The pipe 9 is provided with a valve 10. The tank 6 and receptacle 7^c are provided with suitable inlet and outlet valves. The tank 1, into which the material is introduced, is provided with a pressure-gage 13.

In operation the wood or other material to be treated is placed in the tank and steam introduced therein through the inlet-pipe 3, the steam circulating through the wood and finally passing out of the tank through the pipe 5 into the worm 7^b, where it is condensed and the products of condensation discharged through the pipe 7^d.

Having now described the invention, what I claim as new, and desire to secure by Letters Patent, is—

In a steaming apparatus, a cylindrical tank, provided with a door at each end, a steam-inlet pipe communicating with said tank near one end thereof, a pressure-gage mounted upon said tank and suitably communicating therewith, a vertically and a longitudinally extending outlet-pipe communicating at one end with said tank, a condensing-worm communicating with the other end of said outlet-pipe, a closed tank having a liquid seal therein, and a pipe communicating at its upper end with said condensing-worm and at its lower end projecting into said sealing means.

In testimony whereof I have hereunto set my hand in presence of two subscribing witnesses.

CHARLES WALDREN STANTON.
